TO SANITARY PRODUCTS CORPORATION OF AMERICA, OF PHILADELPHIA, PENN-
SYLVANIA, A CORPORATION OF VIRGINIA.

APPARATUS FOR MAKING PAPER SPOONS AND OTHER FLAT PAPER UTENSILS.

1,394,037.

Specification of Letters Patent.

Patented Oct. 18, 1921.

Application filed September 26, 1919. Serial No. 326,599.

REISSUED

To all whom it may concern:

Be it known that I, GEORGE P. MALLORY, a citizen of the United States, residing at Yorklyn, county of New Castle, State of Delaware, have invented a certain new and useful Improvement in Apparatus for Making Paper Spoons and other Flat Paper Utensils, of which the following is a specification, reference being had therein to the accompanying drawings.

It has been common heretofore to make cheap spoons, that are intended to be used but once, out of vulcanized fiber. Spoons of this character have been formed by dieing out a blank from a sheet of fiber and stamping it to the proper shape. In such case, there has been a great waste of material, usually about 25 per cent., which has been burned because there appeared to be no economical use for it. This has been a dead loss, and owing to the high cost of the raw material, it has constituted a great financial waste. The object of the present invention is to provide a method of and apparatus for making spoons and other articles of flat ware type out of wood pulp paper in such manner that the waste can be redeemed and the article itself shall be harder, stronger and cheaper than those heretofore produced from vulcanized fiber. The invention consists substantially in passing a plurality of laminae of wood pulp paper through a tank containing a solution forming a plastic filler, then running the laminae superposed one upon the other through a series of suitable rolls to leave the proper amount of filler in the laminae, then calendering the laminated sheet and stamping or embossing the design of spoon or other article in the sheet, then passing the sheet to a press which blanks out the article from the embossed sheet.

The invention is more particularly intended to be employed in the manufacture of fiber spoons, and for that reason the drawings show a spoon design. For convenience of description, the word "spoons" will be sometimes employed in the specification, but wherever so used, it is to be understood that it covers any utensil or other article of the flat ware type capable of being made by the machine if the proper dies are substituted.

The invention will be fully understood from the following description when taken in connection with the accompanying draw-

ings, and the novel features thereof will be pointed out and clearly defined in the claims at the close of this specification.

In the drawings, Figure 1 is a side elevation partly in section of a machine embodying the invention.

Fig. 2 is a plan view partly in section of the machine embodying the invention shown in Fig. 1.

Referring now to the drawings, 1 is a stand on which are mounted a plurality of 65 reels 2, 2, 2, which carry rolls of thin paper. In the drawings, three of such rolls are shown, but the number may be more or less according to the number of laminae or thickness desired for the blank sheet from which 70 the spoons are to be formed. Preferably, the sheets are of a width amply sufficient to allow for the length of a spoon cut transversely of the sheet.

A tank 3 is provided adjacent the stand 75 on which the rolls of paper are mounted, said tank containing a plastic solution 33. A rack 4 containing guide rods 5 which serve as spacing rods is pivotally mounted in the tank. In the form of device shown, the 80 rack is provided with arms 6 which are pivoted at 7 within the tank. The said rods 5 are spaced apart from each other and are sufficient in number so that the laminae of paper from the several rolls will each pass 85 separately under its individual guide rod. Said rods thereby guide the laminae through the solution in the tank and maintain them separated from each other so that both faces of each of the laminae will more readily absorb the solution.

The rack is pivoted inside of the tank so that it can be lifted out of the solution to allow threading the paper through the machine, and it is also provided with lock bolts 95 9 to hold it down in place when tension is put on the rolls of paper in feeding them through the machine. The rolls of paper are provided with friction clamps 32 to give the right amount of tension.

Near the upper edge of the tank on the side opposite that on which the reel stand is located are a pair of doctor rolls 10, 10 between which the several laminae of paper pass as they leave the tank. In passing between the doctor rolls, the laminae will be in contact with each other, superposed one upon the other. The doctor rolls are adjustable to

give the right pressure so as to leave the proper amount of the plastic solution in the paper.

- After leaving the doctor rolls, the superposed laminæ pass between two calender rolls 11, 11 mounted on a suitable support 12, to give the proper finish to the compound sheet formed of the several laminæ and thence it passes between two rotary embossing rolls 13, 14. The upper embossing roll 13 is provided with at least one embossing die 15 on its periphery, and the embossing roll 14 is provided with at least one embossing die 16 on its periphery so located as to 10 coöperate with the embossing die 15, one of said dies being a male die and the other a female die, so that when the sheet passes between the said embossing members, the desired form of spoon will be embossed in 15 the sheet to give the proper shape to the bowl and shank and handle. Preferably, the dies are heated by any suitable means. One method is to pass steam through the hollow shafts 20 and 27 on which the rolls 13 and 14 20 are mounted. The peripheries of these embossing dies are curved on an arc of a circle concentric with the rolls 13, 14 on which they are mounted. Preferably, each embossing die is made with duplicate patterns so 25 that each pair of male and female dies will emboss two spoons at each action. In order to leave as little waste as possible, it is preferable to form the two patterns on each die parallel with each other, and with the 30 bowls pointing in opposite directions, as will be seen in Fig. 2. Preferably, there are two embossing dies mounted on each embossing roll, one being diametrically opposite the other so that at each complete rotation of 35 the roll, two sets of the embossing dies will successively come into operation, thus giving a greater capacity of production. Each embossing die from front to rear extends less than one-half the circumference of the embossing roll, that is, the two embossing dies 40 on a single roll do not meet each other, so that there is always a partial rotation of the embossing dies 13, 14 after one set of embossing dies 15, 16 rotates out of contact 45 with the sheet before the opposite set of embossing dies comes in contact with the sheet. As the embossing dies constitute the sheet feed, there will thus be an intermittent movement of the sheet although the rolls 50 rotate continuously, the dwell of the sheet continuing from the time one set of embossing dies passes out of engagement with the sheet until the next set of embossing dies comes into engagement with the sheet to 55 continue the feed. There will thus be two spoons embossed at a time by each pair of dies, and four spoons at each complete rotation of the roll, with a dwell of the sheet between the action of the two sets of dies. 60
- 65 After passing between the embossing dies,

the sheet is guided between the two blanking out members 17, 18 of a press.

The press is a power press, the upper die 17 being movable vertically and driven by a suitable driving connection between the shaft 20 on which the upper embossing roll 13 is mounted and the shaft 21 which actuates the plunger 22 which carries the upper blanking die 17. The driving connection shown consists of a chain 19 which runs over a sprocket 23 on the shaft 20 and over a sprocket 24 on the shaft 21. Mounted on shaft 20 is a spiral gear 25 which meshes with a spiral gear 26 on a shaft 27 of the embossing roll 14, said shaft 27 having mounted thereon a driving pulley which is driven by any suitable means.

The shaft 21 is connected with suitable mechanism whereby the plunger 22, and therefore the movable blanking die 17, is 85 vertically reciprocated in the well known manner of operating power presses. It is not deemed necessary to show the details of construction. It is timed in such manner that the latter part of the downward stroke 90 of the blanking member 17 will take place during the dwell in the process of feeding the sheet and will be lifted from the sheet before the forward feed again begins.

In Fig. 2, a series of spoon embossings 95 is shown as they appear embossed in the strip after passing between the embossing rolls before the blanks are cut from the sheet. The spoon blanks are then cut out by the blanking dies 17 and 18. The spoons drop 100 down through the dies into a suitable receptacle 30. The openings 31 in the sheet show where the spoons have been died out.

The plastic solution is simply a bonding material for cementing the laminæ of paper 105 together, and by giving the embossing rolls the proper degree of heat, the bonded paper becomes hard. The degree of heat, however, is not sufficient to destroy the fiber of the paper, and the scrap can be returned to the 110 paper mill, put through the beaters, and used over again.

What I claim is:—

1. An apparatus for forming paper spoons or other articles, having a pair of coöperating rotary embossing rolls between which a sheet of material from which the articles are to be formed is fed, each roll having on its periphery an embossing die, said dies extending only partially around the circumference of the roll and being raised above the surfaces of the roll so that there is a space between the two ends of the die which does not engage with the sheet, thereby causing a dwell in the movement of the sheet between the time that the last engaging portion of the die passes out of engagement with the sheet and the time when the first engaging portion of the die again comes in contact with the sheet, in combination with a plunger 22 which carries the upper blanking die 17, the plunger 22 being movable vertically and driven by a suitable driving connection between the shaft 20 on which the upper embossing roll 13 is mounted and the shaft 21 which actuates the plunger 22 which carries the upper blanking die 17. The driving connection shown consists of a chain 19 which runs over a sprocket 23 on the shaft 20 and over a sprocket 24 on the shaft 21. Mounted on shaft 20 is a spiral gear 25 which meshes with a spiral gear 26 on a shaft 27 of the embossing roll 14, said shaft 27 having mounted thereon a driving pulley which is driven by any suitable means.

nation with a pair of cutting dies between which the sheet is fed from the embossing rolls, said cutting dies being shaped to a contour to cut out the embossed blank from the sheet, and means for driving the embossing dies and the cutting dies in such timed relation to each other that the cutting dies will be operated during the dwell in the travel of the sheet occasioned by the blank spaces between the two ends of the embossing dies.

2. An apparatus for forming paper spoons or other articles, having a pair of coöperating rotary embossing rolls between which a sheet of material from which the articles are to be formed is fed, each roll having on its periphery an embossing die, one of said dies being a male die and the other a female die, the periphery of each die being curved on the arc of a circle concentric with the roll on which it is mounted, the said two dies being so disposed on the peripheries of their respective rolls that at each rotation of the rolls the sheet which is being fed through will be engaged by both of said dies, thereby embossing and feeding the

sheet, said dies extending only partially around the circumference of the roll and being raised above the surfaces of the roll so that there is a space between the two ends of the die which does not engage with the sheet, thereby causing a dwell in the movement of the sheet between the time that the last engaging portion of the die passes out of engagement with the sheet and the time when the first engaging portion of the die again comes in contact with the sheet, in combination with a pair of cutting dies between which the sheet is fed from the embossing rolls, said cutting dies being shaped to a contour to cut out the embossed blank from the sheet, and means for driving the embossing dies and the cutting dies in such timed relation to each other that the cutting dies will be operated during the dwell in the travel of the sheet occasioned by the blank spaces between the two ends of the embossing dies.

In testimony whereof I affix my signature.

GEORGE P. MALLORY.
